UNITED STATES PATENT OFFICE.

PETER MURRAY, JR., OF NEWARK, NEW JERSEY, ASSIGNOR TO THE BACKUS MANUFACTURING COMPANY, OF SAME PLACE.

ROTARY FAN.

SPECIFICATION forming part of Letters Patent No. 349,855, dated September 28, 1886.

Application filed May 12, 1886. Serial No. 201,931. (No model.)

To all whom it may concern:

Be it known that I, PETER MURRAY, Jr., of Newark, in the county of Essex and State of New Jersey, have invented certain new and useful Improvements in Rotary Fans, of which the following is a specification.

This invention relates to an improved rotary fan-shaft of that class which is suspended from the ceiling and adapted for agitating the air in stores, counting-rooms, restaurants, &c.; and the invention consists of the combination of a rotary fan-shaft supported in bearings, a hanger-frame suspended from the ceiling, a driving-shaft, a friction-gear for transmitting rotary motion from the driving-shaft to the fan-shaft, a fan attached to the lower end of the fan-shaft, a sleeve keyed to the fan-shaft above the lower bearings of the same, a spiral balancing-spring interposed between said bearing and the sleeve, and means for raising or lowering the fan-shaft and throwing its friction-gear in or out of mesh, so as to rotate or stop the fan.

In the accompanying drawings, Figure 1 represents a side elevation of my improved rotary fan-shaft; and Fig. 2 is a detail vertical section of a portion of the same, drawn on a larger scale.

Referring to the drawings, A represents a supporting hanger-frame, which is suspended from the ceiling in any suitable manner, and provided with bearings b and a rotary fan-shaft B. To the lower end of the rotary fan-shaft B is attached the fan C. To the upper end of the fan-shaft B is applied a friction-disk, b' , which meshes with the friction-disk b^2 , keyed to the driving-shaft D, which is suspended in suitable hangers (not shown in the drawings) from the ceiling, and in a tubular bearing, D', pivoted to lugs of one of the legs of the hanger-frame A, as shown in Fig. 1. The weight of the fan-shaft B and fan C is supported by a spiral spring, e, which rests on a loose collar, e' , supported on the lower bearing, b, of the hanger-frame A, said spring being inclosed by a sleeve, e^2 , that is attached by a set-screw, e^3 , to the fan-shaft B, as shown in Fig. 2. A collar, f, is screwed or otherwise

applied to the hanger-frame A below the lower bearing, b, and provided with a recess, f', which recess is engaged by a fixed pin, f^2 , on the fan-shaft. The fan-shaft is taken hold of by a button, g, below the hub of the fan C, when it is desired to stop the fan, and pulled downward against the tension of the spring e until the pin f^2 clears the recess of the collar f and abuts against the lower edge of the collar. In this position of the fan-shaft B, the friction-disk b' is separated from the friction-disk b^2 on the driving-shaft D, so that the transmission of motion from the driving-shaft to the fan-shaft is interrupted.

For rotating the fan C, the button g is taken hold of and the fan shaft B turned until the pin f^2 enters the recess f' of the collar f by the lifting-action of the spring e, which also raises the fan-shaft B and its friction-disk d' , and causes the meshing of the latter with the friction-disk d of the driving-shaft, whereby rotary motion is imparted to the fan-shaft and fan.

Having thus described my invention, I claim as new and desire to secure by Letters Patent—

The combination of a supporting hanger-frame, a fan-shaft supported in bearings of said frame, a fan attached to the lower end of the fan-shaft, a driving-shaft, a friction-gear transmitting motion from the driving-shaft to the fan-shaft, a spiral spring resting on a collar of the hanger-frame, a sleeve attached to the fan-shaft and inclosing said spiral spring, a recessed collar attached to the hanger-frame, and a pin on the fan-shaft which engages or disengages the recessed collar when raising or lowering the fan-shaft, so as to throw the fan in or out of motion, substantially as set forth.

In testimony that I claim the foregoing as my invention I have signed my name in presence of two subscribing witnesses.

PETER MURRAY, JR.
